UNITED STATES PATENT OFFICE.

EDOUARD HANNON, OF BRUSSELS, BELGIUM, ASSIGNOR TO THE SOLVAY PROCESS COMPANY, OF SYRACUSE, NEW YORK, A CORPORATION OF NEW YORK.

ELECTROLYTIC APPARATUS.

SPECIFICATION forming part of Letters Patent No. 742,863, dated November 3, 1903.

Application filed October 4, 1898. Serial No. 692,602. (No model.)

To all whom it may concern:

Be it known that I, EDOUARD HANNON, a subject of the King of Belgium, residing at Brussels, Belgium, have invented a new and useful Electrolytic Apparatus, (for which I have filed applications for foreign Letters Patent as follows: in Belgium, No. 134,177, March 5, 1898; in Great Britain, No. 7,470, March 28, 1898; in Germany, No. S. 11,225/75, March 18, 1898; in Russia, No. 4,602, May 4/16, 1898; in France, No. 266,676, June 14, 1898; in Switzerland, No. 18,973, July 28, 1898; in Austria, August 12, 1898, and in Hungary, No. 12,054, August 25, 1898,) of which the following is a specification.

This invention has for its object the production of a particularly simple, practical, and effective apparatus for effecting the electrolysis of alkaline chlorids and other salts in the presence of a fluid electrode, as mercury; and to this end said invention consists in the combination, construction, and arrangement of the component parts of an electrolytic apparatus, as hereinafter fully described, and pointed out in the claims.

In describing this invention reference is had to the accompanying drawings, forming part of this specification, in which like letters indicate corresponding parts in all the views.

Figure 1 is a vertical sectional view of one form of my electrolytic apparatus. Fig. 2 is a horizontal sectional view taken on line 2 2, Fig. 1.

In the present constructions of electrolytic apparatus intended for the electrolysis of alkaline chlorids and other salts in the presence of a fluid electrode, as mercury, it is customary to effect the circulation of the fluid electrode by rocking the apparatus, by causing the electrode to flow along an inclined bottom or in spiral channels, or by displacing the same by pistons, plungers, and pumps. These apparatus are more or less objectionable, since if the movement of the fluid electrode is arrested the apparatus are deprived of said fluid electrode, although the current continues to pass.

My invention is radically different from the prior types of electrolytic apparatus, for the

reason that it is so constructed that the surface of the fluid electrode adjacent to the electrolyte is continually removed from the remaining portion of the electrode, so as to constantly present a fresh surface to the metal being liberated on said electrode. The alkaline amalgam forms in greatest quantity at the surface of the fluid electrode adjacent to the electrolyte and tends to remain on said surface by reason of its lightness. Consequently my invention is particularly practical and effective, since the surface of the fluid electrode, which is richest in alkaline metal, is positively and readily withdrawn without displacement of the remaining portion of the fluid electrode or agitation of said surface during its removal from said remaining portion of the electrode.

My electrolytic apparatus comprises a receptacle A for receiving the electrolyte and a fluid electrode, as mercury, and suitable means for removing the surface of the electrode adjacent to the electrolyte from the remaining portion of said electrode. In the preferable construction of my invention the surface of the fluid electrode adjacent to the electrolyte overflows without agitation in a substantially horizontal plane from a chamber a within the receptacle A to a second chamber a', also within the receptacle A. Said chambers are generally provided in the base of the receptacle A, and the fluid electrode therein rests upon the bottom wall a² of said receptacle. The wall a³, over which the fluid electrode overflows from the chamber a, is preferably of suitable height to maintain the level of the fluid electrode in the receptacle A above the level of said electrode in the outlet-conduit, presently described, and may be fixed in position, although it is usually provided with suitable adjusting means, as screws a⁴, for varying the level of the fluid electrode within the chamber a.

The fluid electrode, as mercury, is preferably admitted to the chamber a by a supply-reservoir a⁵ and is withdrawn from the chamber a' by an outlet-conduit a⁶. The reservoir a⁵ is generally provided within the receptacle A and communicates with the side of the chamber a opposite to the wall a³ and with

an inlet-conduit a^7 , which discharges into the reservoir below the level of the fluid electrode therein. The fluid electrode is supplied to the inlet-conduit a^7 from any suitable source, as a fluid-elevator a^8 , which may be of any desirable form, size, and construction. The illustrated fluid-elevator consists of a closed shell partly filled, as indicated by the dotted line therein in Fig. 1, with the material, as mercury, forming the fluid electrode, an inlet-conduit for said material, an outlet-conduit leading from a point below the level of the material to the inlet-conduit a^7 , and a third conduit for discharging a suitable fluid under pressure above said material and forcing the same through said outlet-conduit. The outlet-conduit a^6 usually opens from the chamber a' below the level of the fluid electrode within said chamber and is so arranged and connected that the level of the fluid electrode within said chamber and conduit is below the level of the fluid electrode in the chamber a . The described means for admitting the fluid electrode to the chamber a and for removing the same from the chamber a' is particularly simple in construction and effective in operation; but it is obvious that any other suitable means may be used for said purpose, if desired.

The outlet-conduit a^6 withdraws from the receptacle A only the overflow from the chamber a , and therefore a body of the fluid electrode remains continually within the receptacle A even though the flow of said electrode to the chamber a is arrested. As the withdrawal of all of the fluid electrode from the receptacle A is sometimes necessary, said receptacle may be inclined by any suitable means, as a screw a^9 , and may be provided with an outlet-conduit (not illustrated) having means for controlling the passage therethrough. The described means for removing all of the fluid electrode from the receptacle A forms no part of my present invention, and consequently it is unnecessary to further illustrate and describe the same.

The electrolyte within the receptacle A contains the alkaline chlorids or other salts to be electrolyzed, is generally supported upon the fluid electrode in the chambers a and a' , and receives a suitable electrode, as a plurality of conductors a^{10} , which are usually connected to one of the branches or conductors b of an electric circuit having its other branch or conductor b' connected to the wall a^2 of the receptacle A. The electrolyte is preferably withdrawn from the receptacle in the same direction as that of the movement of the upper surface of the electrode from the chamber a into the chamber a' . The means for conducting the electrolyte to and from the receptacle A is here illustrated as inlet and outlet conduits $a^{11} a^{12}$, which are arranged so as to communicate with the receptacle A at points directly above the conduits $a^7 a^6$. It is obvious, however, that the electrolyte may be conducted to and from the re-

ceptacle A by any other suitable means instead of the conduits $a^{11} a^{12}$.

The fluid electrode combined in my electrolytic apparatus may be recovered by any suitable means, unnecessary to herein illustrate and describe.

In the operation of my electrolytic apparatus there is no limitation to a predetermined discharge, as in other types of electrolytic apparatus, since any discharge may be employed which is found to be most advantageous without affecting the proper utilization of the electric current. Indeed, solid amalgam floating on the surface of the fluid electrode might be produced, as its discharge presents no difficulty.

The construction and operation of my electrolytic apparatus will now be readily understood upon reference to the foregoing description and the accompanying drawings, and it will be noted that considerable change may be made in the construction and arrangement of the component parts of said apparatus without departing from the spirit of my invention.

Having thus fully described my invention, what I claim as new, and desire to secure by Letters Patent, is—

1. An electrolytic apparatus comprising a receptacle for receiving the electrolyte, a fluid electrode and a second electrode, and means for causing the surface of the fluid electrode adjacent to the electrolyte to flow without agitation in a substantially horizontal plane from the contiguous portion of the fluid electrode, substantially as and for the purpose described.

2. An electrolytic apparatus comprising a receptacle for receiving the electrolyte, a fluid electrode and a second electrode, means for adding to the fluid electrode a fresh supply of the material forming said electrode, and means for causing the surface of the fluid electrode adjacent to the electrolyte to flow without agitation in a substantially horizontal plane from the contiguous portion of the fluid electrode, substantially as and for the purpose set forth.

3. An electrolytic apparatus comprising a receptacle for receiving the electrolyte, a fluid electrode and a second electrode, means for adding to the lower portion of the fluid electrode a fresh supply of the material forming said electrode, and means for removing the upper surface of the fluid electrode by gravity without agitation of said surface, the underlying bed of the electrode or the contiguous surface of the electrolyte, substantially as and for the purpose specified.

4. An electrolytic apparatus comprising a receptacle for receiving the electrolyte, a fluid electrode and a second electrode, means for adding to the lower portion of one end of the fluid electrode a fresh supply of the material forming said electrode, and means for removing the upper surface of the fluid electrode without agitation of said surface and for caus-

ing the same to overflow at the upper portion of the opposite end of the fluid electrode, substantially as and for the purpose set forth.

5. An electrolytic apparatus comprising a receptacle for receiving the electrolyte, said receptacle being provided with a chamber for receiving a fluid electrode, and a second chamber for receiving an overflow of the fluid electrode from the first chamber, means for causing the surface of the fluid electrode in the first chamber adjacent to the electrolyte to flow without agitation in a substantially horizontal plane from the contiguous portion of the electrode and to overflow into the second chamber and a second electrode in said receptacle, substantially as and for the purpose described.

6. An electrolytic apparatus comprising a receptacle for receiving the electrolyte, said receptacle being provided with a chamber for receiving a fluid electrode, a second chamber arranged at one side of the first chamber for receiving an overflow of the fluid electrode therefrom, and a supply-reservoir communicating with the opposite side of the first chamber for adding to the lower portion of the fluid electrode a fresh supply of the material forming said electrode and causing the upper surface of the fluid electrode to flow by gravity without agitation in a substantially horizontal plane and to overflow into the second chamber, an outlet-conduit connected to the second chamber and a second electrode in the receptacle, substantially as and for the purpose specified.

7. An electrolytic apparatus comprising a receptacle for receiving the electrolyte and a fluid electrode, means for removing the upper surface of the electrode from above the underlying body thereof, and means for withdrawing the electrolyte from the receptacle in the same direction as that of the movement of the upper surface of the fluid electrode, substantially as and for the purpose specified.

45 8. An electrolytic apparatus comprising a receptacle for receiving the electrolyte, said receptacle being provided with a chamber for

receiving a fluid electrode, a second chamber for receiving an overflow of the fluid electrode from the former chamber, and means for withdrawing the electrolyte from the receptacle in the same direction as that of the movement of the overflow of the fluid electrode, substantially as set forth.

9. An electrolytic apparatus comprising a receptacle for receiving the electrolyte, said receptacle being provided with a plurality of chambers containing a fluid electrode and arranged beneath the level of the electrolyte, one chamber having the upper surface of the fluid electrode therein arranged above the level of the fluid electrode in a second chamber and movable into said second chamber from above the underlying body of said electrode, and means for withdrawing the electrolyte from the receptacle in the same direction as that of the movement of the upper surface of the fluid electrode from the first chamber into the second chamber, substantially as described.

10. An electrolytic apparatus comprising a receptacle for receiving the electrolyte, said receptacle being provided with a plurality of chambers containing a fluid electrode and arranged beneath the level of the electrolyte, one chamber having the upper surface of the fluid electrode therein arranged above the level of the fluid electrode in a second chamber and movable into said second chamber from above the underlying body of said electrode, conduits communicating with said two chambers beneath the level of the fluid electrode therein, and additional conduits communicating with the receptacle above the former conduits, substantially as set forth.

In testimony whereof I have hereunto signed my name, in the presence of two attesting witnesses, at Brussels, Belgium, this 1st day of September, 1898.

EDOUARD HANNON.
